UNITED STATES PATENT OFFICE.

LOUIS A. MAXSON, OF CLAREMONT, NEW HAMPSHIRE, ASSIGNOR TO SULLIVAN MACHINERY COMPANY, A CORPORATION OF MASSACHUSETTS.

MINING MACHINE.

Application filed August 31, 1925. Serial No. 53,554.

This invention relates to mining machines, and more particularly to mining machines of the type which are adapted to cut kerfs while sliding over the mine bottom and which are fed and guided by flexible feeding means and feed operating and controlling members which cooperate directly with the flexible feeding means.

In the operation of mining machines according to the room and pillar method, machines having cutter bars extending longitudinally of their frames are moved and guided by flexible feeding means during cutting, positioning, and loading onto and unloading from the trucks which serve to support the machines during travel from one working face to the next. Depending upon the hardness of the coal and upon other conditions the cutting speed of the machine may vary widely, but ordinarily is between one and three feet per minute. During sumping, the extent of the cutting front being diminished, the speed may be substantially higher, but with hard coal will ordinarily be perhaps two feet per minute while in rather soft cutting and with other conditions favorable it may exceed five feet per minute. During positioning, and loading and unloading, the feeding speed may be a good many times as high as during cutting. It will therefore be apparent that a machine may very advantageously be provided with mechanism providing cutting, sumping, and moving speeds.

Among the objects of the present invention is the provision of an improved mining machine having improved feeding means. A more specific object of the invention is to provide improved mining machine feeding means providing predetermined speeds adapted to cutting, sumping, and moving or positioning. A further object of the invention is to provide improved feeding means of the epicyclic type in which through the different cooperation and actuation of the gearing elements a plurality of speeds adapted to the needs of the machine operation may be secured. A still further object of the invention is to provide improved feed driving mechanism of the epicyclic type in which through the different coaction of the gearing elements a pair of driving members

may provide a greater number of feeding speeds. Other objects and advantages of the invention will subsequently appear.

The foregoing objects may well be accomplished by the embodiment of the invention in a machine having a frame slidable over the mine bottom during cutting and provided with a projecting cutter bar supporting orbitally moving cutting elements. For feeding and guiding, the machine is preferably provided with rotatable feed operating and controlling means adapted to cooperate directly with flexible feeding means: preferably a pair of rotatable feed operating and controlling members cooperating with flexible feeding portions, which may either be separate or may be the opposite extremities of a continuous flexible feeding member. Actuating and controlling means for the feed operating and controlling members preferably assumes a construction adapted to provide three predetermined feeding speeds respectively adapted for cutting, sumping and machine moving or positioning. The several speeds are preferably obtained by the cooperation of mechanism of the epicyclic or differential type and comprising a set of coaxial members for each feed operating and controlling member, two of the coaxial members having coaxial gears associated therewith and the third carrying planet means cooperating with the coaxial gears, means being provided to effect rotation of one or more of said coaxial members, including means for effecting reverse rotation of one of the same, means for connecting another of said members to a feed operating and controlling member also being provided. Separate braking devices are also preferably provided for the feed operating and controlling members, and where a plurality of sets of coaxial members are employed similar actuating and controlling means for corresponding members of each set are preferably provided. Preferably self-locking worm gearing may be used to actuate the positively rotated coaxial members, and when a plurality of sets of the latter are used the worms are preferably vertically arranged in the central longitudinal vertical plane of the machine. If desired, auxiliary locking means may be used with

the worm gearing to lock any work which may be serving as a reaction member, whereby greater leads may be employed. A common motor preferably serves for the cutting mechanism drive and feeding, and both drives may be from the rear end of the motor.

In the accompanying drawings in which for purposes of illustration there is shown 10 an illustrative embodiment of the invention,

Fig. 1 is a view partially in plan, but mainly in longitudinal horizontal section through the feeding mechanism of a mining machine, certain parts being omitted.

15 Fig. 2 is a central vertical section on the line 2—2 of Fig. 1.

Fig. 3 is a fragmentary section on the line 3—3 of Fig. 2.

Fig. 4 is a vertical section on the line 4—4 20 of Figs. 1 and 2.

Referring to the drawings, 1 represents the main frame of a mining machine, which carries at its forward end in rigid longitudinally projecting relation a cutter bar 2 25 about which a cutter chain 3 is adapted to be circulated under the actuation of a cutter chain driving sprocket 4 journaled in a manner hereinafter described upon the machine frame 1. A motor 5 having an armature shaft 6 provided with a driving pinion 7 is mounted upon the machine frame 1 in a position above the rear end of the cutter bar and supplies power for actuating the cutting mechanism and for effecting feeding 30 of the machine during cutting and at other times. The pinion 7 drives a gear 8 secured in non-rotative relation to a horizontal shaft 9 journaled in bearings 10 upon the frame. At its rear end the shaft 9 carries a bevel 40 driving pinion 12 which meshes with a bevel gear 13 rotating upon a vertical axis, the gear 13 being rigidly mounted upon a vertical shaft 14 which is journaled in the bearings 15 upon the frame 1. At its lower end 45 the shaft 14 carries a spur driving pinion 16 which meshes with and drives a driving gear 17 coaxial with the cutter chain driving sprocket 4. The gear 17 is keyed to a shaft 18 as at 19 and is provided with a sleeve 20 upon which a bearing sleeve 21 carrying the cutter chain driving sprocket 4 is rotatably mounted. At its upper end the sleeve 21 carries internal clutch teeth 22 with which a cooperating set of clutch teeth 23 formed 50 upon a vertically slidable sleeve 24 may engage. The sleeve 24 is splined as at 25 to the shaft 18 and may be slid up and down upon said shaft by a clutch shifter 26 which may have any suitable actuating means as, 55 for example, a manually controlled supporting shaft 27. The exterior periphery of the cutter chain driving sprocket 4 is journaled in bushings 32 and 33 mounted in different portions of the frame 1 and it will 60 be observed that the gears 16 and 17 are en-

closed in a chamber 35 formed in the frame beneath the plane of the cutter chain driving sprocket.

Within a chamber 40 above the cutting mechanism is enclosed the illustrative embodiment of my improved feeding mechanism. This feeding mechanism is adapted to effect rotation in opposite directions upon reversal of the motor 6 and in either direction at three different predetermined speeds 75 respectively adapted to feed during cutting, feed during sumping, and feed during moving onto and off of the truck and during positioning, of a pair of feed operating members 41 and 42 which are herein of the rope or cable winding type, although they may obviously take the form of feed chain engaging sprockets where it is desired to employ a continuous chain in place of separate feed cables. The feed operating members 41 and 42 are each journaled on bearings 43 upon projections 44 carried by the frame 1. The actuating mechanism for each of these feed operating members is the same as for the other and accordingly but one side of the feeding mechanism needs to be described. Referring therefore to the feed operating member 41 it will be observed that the member 44 supports it for rotation upon a longitudinally extending horizontal axis and that it is traversed by a longitudinally extending horizontal shaft 46 which carries at its rear end a sleeve 48 having peripheral clutch teeth 49. The feed operating member 41 is keyed as at 50 to a sleeve 51 which has peripheral clutch teeth 52 formed thereon and adapted to be connected by a sliding clutch member 53 to the clutch teeth 49 to connect the drum to the shaft 46. The clutch 53 may also be employed to connect the teeth 49 to a truck driving member (shown in dotted lines) if desired.

The shaft 46 extends through an opening 54 in the projection 44 and is journaled in a bearing 55 in the end plate 56 of the main frame. Inside of this plate it carries a sleeve 57 keyed thereto at 58 and having in interlocking engagement therewith a series of friction clutch discs 59 which alternate with the discs 60 of a second series carried in non-rotative relation by a member 61 keyed as at 62 within the frame 1. From the description so far given it will be obvious that the shaft 46 may be braked upon the application of pressure to the clutch discs 59 and 60. Next to the sleeve 57 is a sleeve 64 which is surrounded by a member 65 which cooperates with a member 65^a in enclosing the friction clutch mechanism. Between the members 65 and 65^a is an annular opening 66 through which fingers 67 extend and act to load the friction clutch. The fingers 67 are carried upon a longitudinally slid able clutch sleeve member 68. Forward of the sleeve 64 there is keyed to the shaft 100 105 110 115 120 125 130

46 a further sleeve 70 to which a plurality of friction clutch discs 71 are secured in non-rotative relation. The sleeves 70 and 64 are surrounded by the cooperating members 72 and 73 of a friction clutch housing within which the discs 71 are disposed and the member 72 carries in non-rotative relation thereto a series of clutch discs 75 alternating with the clutch discs 71. Between the members 72 and 73 is an annular opening 76 corresponding to the opening 66 and clutch operating fingers 77 directed oppositely to the fingers 67 are adapted to force the discs 71 and 75 into tight frictional engagement.

15 The clutch enclosing casing 72 has a sleeve 78 which is surrounded by and journaled in a ball bearing 80 carried by the main frame and forwardly of the ball bearing there is keyed to the sleeve 78 a planet carrying annulus 81 provided with a plurality of forwardly extending stub shafts 82 surrounded by ball bearings 83 upon which planet gears 84 are journaled. Coaxial with the shaft 46 is a shaft 85 journaled at its forward end in 25 a bearing 86 in the frame and having mounted thereon in non-rotative relation thereto a worm wheel 87 which constitutes a driving member for the shaft. At its rear end the shaft 85 has gear teeth 88 formed thereon which mesh with the teeth of the planet gears 84 and under some circumstances cooperate in driving the same. Just forward of the gear portion 88 is a bearing 89 carried by the frame, in which a sleeve 90 surrounding the shaft 85 is journaled. The sleeve 90 carries an internal gear 91 whose periphery is in the form of a worm wheel 92, the internal gear 91 also engaging the teeth of the planet gears 84.

20 It will be understood that the construction described with respect to the drum 41, shaft 46 and all the parts associated therewith is precisely duplicated in the mechanism employed for the drive of the drum 42.

45 For the purpose of driving the worm wheels 87 and 92 there are arranged for rotation upon vertical axes lying in the central longitudinal vertical plane of the machine a pair of driving worms 101 and 102 respectively constituting driving elements for the worm wheels 87 and for the worm wheels 92. The worm 102 is mounted in non-rotative relation to the shaft 18 and is fixed against longitudinal movement thereon. The worm 101 is mounted in non-rotative relation to a shaft 103 which is journaled in bearings 104 and 105 respectively at its lower and upper ends. The lower end of the shaft 103 is rotatably surrounded by a sleeve 106 carrying a spur gear 107 which meshes with and is constantly driven by a gear 108 splined as at 109 to the shaft 18. Adjacent its upper end the shaft 103 is rotatably surrounded by a gear 110 which constantly meshes with and is driven by a gear 111 (see Fig. 3) which in

turn meshes with a gear 112 splined to the shaft 18 adjacent the upper end of the latter which is journaled in a bearing 113. The gear 110 has a depending sleeve portion 114. The sleeve 106 and the sleeve 114 abut 70 against the opposite ends of the worm and each has splined thereto a clutch member. The latter are designated 115 and 116 and are selectively engageable with teeth 117 and 118 on the worm 101. On elevation of the 75 clutch members 115 and 116 the worm will be connected through clutch 115 and teeth 117 to the sleeve 106 and will be driven by the latter and it will be obvious that the downward movement of the clutches may 80 connect the worm with the sleeve 114 whereby the worm may be driven by the gear 110. When the clutch 116 is in midposition the worm is allowed to remain stationary and locks its worm wheels 87.

85 Clutches 115 and 116 are simultaneously movable by shippers 119 and 120 mounted on transverse shafts 121 and 122 and connected by link means 123. Any suitable self-locking handle may be employed to simultaneously rotate the shafts and such a handle is shown at 124. Suitable guide sheaves 130, 131 and 132 are arranged in pairs on vertical axes in positions to be cut by planes tangent to the winding surfaces of the drums 90 41 and 42 and respectively above and below such surfaces, and guide sheaves 133 are arranged at the front end of the machine frame adjacent the plane of the cutter bar to enable cutting in opposite directions. 95 The clutch loading members 68 are controlled, as best shown in Fig. 4, by a pair of handles 136 and 137 which respectively operate coaxial controlling members 138 and 139 for the two clutch loading members 68 and which may be placed at either side of the machine for reverse cutting.

100 The mode of operation of the feed operating gear can be readily understood from the description so far given. It will be appreciated that the speeds transmitted to the feed operating members will depend in large measure upon the particular nature of the gearings. For the purpose of simplicity a gearing in which the cutting speed is roughly one-half the summing speed and the machine moving or positioning speed is roughly six times the cutting speed, has been disclosed. It will be appreciated that by increasing the speed multiplication between 110 the shaft 18 and the worm 101 the feeding speed may be increased. For example, if the multiplication were four to one instead of two to one as illustrated, the machine moving speed would be ten times the cutting speed. The speed of the planet carrier 81 which determines the speed of rotation of the feed operating member is equal to the speed of the worm wheel 92 multiplied by the quotient obtained by dividing the num- 115 120 125 130

ber of teeth upon the internal gear 91 by the sum of the number of the teeth upon this gear and upon the pinion 88 plus or minus the product of the speed of the pinion 88 multiplied by a factor equal to the quotient obtained by dividing the number of teeth on the pinion 88 by the sum of the teeth on the pinion 88 and internal gear 91. It will be noted that the worm 102 constantly drives the gears 91 in such direction as to cause the feed operating members 41 and 42 to rotate respectively clockwise and counter-clockwise when the motor is running in a direction appropriate to cutting from right to left. The cutting speed is obtained when the worm 101 is run in the same direction as the worm 102, it being observed that this is accomplished through the gears 112, 111, and 110 and with the proportions disclosed for purposes of illustration the worm 101 will then be rotated at one-half the speed of the worm 102. It may then be noted that the lead of the worm 101 is three times the lead of the worm 102 and accordingly that the angular rate of rotation of the worm wheel 87 will be one and one-half times that of the worm wheel 92. The worm wheel 87, however, drives the gear 88 which has only one-third the number of teeth that are provided by the internal gear 91. Accordingly, the rotation of the gear 88 in a direction opposite to the rotation of the gear 91 in the manner described will serve simply to halve the speed transmitted to the shafts 46 and so to the feed operating members. The speed so obtained will correspond to the cutting speed and be equal to one-half the sumping speed obtained through the drive of the worm 102 alone while the worm 101 is stationary and acting as a lock and the gear 91 serving as a reaction gear. The machine moving speed is obtained when the gear 108 driving the gear 106 effects a rotation of the worm 101 at twice the speed of rotation of the worm 102. In view of the direction and difference in lead of the worms, the gear 88 will make six revolutions to each one of the internal gear 91, but in the same direction with the result that the shaft 46 will be driven six times as fast as during cutting operation. Now that the speed ratios are understood, it will be evident that a flexible feeding member 135 passing from a jack adjacent the left hand rib around the guide sheave 133 and wound in a clockwise direction upon the drum 42 will be wound in at any of the three speeds mentioned depending upon the position of the clutch members 115 and 116, and it will be noted that a flexible feeding member mounted in a similar manner upon the feed operating member 41 would likewise tend to be wound in, but may be wholly relieved from the influence of the feed operating driving mechanism and braked as desired by shifting the

clutch loading member 68 to a position wherein the driving clutch is unloaded and its shaft 46 frictionally connected to the member 61 which is keyed to the main frame. It will therefore be apparent that, depending upon the position of the upper clutch 68, sumping can be effected or the receding flexible feeding member permitted to pay out as desired, and that the advance flexible feeding portion 135 may be drawn in at any of the three speeds needed. 75

While I have in this application specifically described one form which my invention may assume in practice, it will be understood that this form of the same is shown for purposes of illustration and that the invention may be modified and embodied in various other forms without departing from its spirit or the scope of the appended claims. 80 85

What I claim as new and desire to secure by Letters Patent is:

1. In a mining machine, a motor, cutting mechanism driven thereby, and feeding means including a feed operating member adapted to cooperate directly with flexible feeding means, and means for actuating and controlling rotation of said member including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed. 90 95 100 105

2. In a mining machine, a motor, cutting mechanism driven thereby, and feeding means including a feed operating member adapted to cooperate directly with flexible feeding means, and means for actuating and controlling rotation of said member including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed, said last mentioned means comprising means for rotating one of said other coaxial members separately or both simultaneously. 110 115 120 125

3. In a mining machine, a motor, cutting mechanism driven thereby, and feeding 130

adapted to cooperate directly with flexible feeding means, and means for actuating and controlling rotation of said member including a plurality of coaxial members rotating 5 on horizontal longitudinally extending axes, two of which support coaxial gear members and another of which supports planet means meshing with said gear members, means for operatively connecting one of said coaxial 10 members to said feed operating member, and means cooperating with said other coaxial members to cause said member operatively connected with said feed operating member to rotate the latter at a predetermined cutting 15, 75, 80, 85, 90, 95, 100, 105, 110, 115, 120, 125 speed.

10. In a mining machine, a motor, cutting mechanism driven thereby, and feeding 20 means including a feed operating member adapted to cooperate directly with flexible feeding means, and means for actuating and controlling rotation of said member including a plurality of coaxial members rotating 25 on horizontal longitudinally extending axes, two of which support coaxial gear members and another of which supports planet means meshing with said gear members, means for operatively connecting one of said coaxial 30 members to said feed operating member, and means cooperating with said other coaxial members to cause said member operatively connected with said feed operating member to rotate the latter at a predetermined cutting 35, 80, 85, 90, 95, 100, 105, 110, 115, 120, 125 speed, said last mentioned means comprising means for rotating one of said other coaxial members separately or both simultaneously.

11. In a mining machine, a motor, cutting mechanism driven thereby, and feeding means including a feed operating member adapted to cooperate directly with flexible 45, 50, 55, 60, 65, 70, 75, 80, 85, 90, 95, 100, 105, 110, 115, 120, 125 feeding means, and means for actuating and controlling rotation of said member including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial 60, 65, 70, 75, 80, 85, 90, 95, 100, 105, 110, 115, 120, 125 members to cause said member operatively connected with said feed operating member to rotate the latter at a predetermined cutting, a predetermined higher sumping, and a predetermined still higher machine moving speed, said last mentioned means comprising means for rotating one of said other coaxial members separately or both simultaneously in the same direction.

12. In a mining machine, a motor, cutting 65 mechanism driven thereby, and feeding

means including a feed operating member adapted to cooperate directly with flexible feeding means, and means for actuating and controlling rotation of said member including a plurality of coaxial members rotating 70 on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher 80 sumping, and a still higher machine moving speed, said last mentioned means comprising means for rotating one of said other coaxial members separately or both simultaneously in opposite directions. 85

13. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed. 95

14. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed, said last mentioned means comprising means for rotating one of said other coaxial members separately or both simultaneously. 110

15. In a mining machine, a motor, cutting mechanism driven thereby, and feeding 130

- means including a plurality of feed operating members each adapted to cooperate directly with flexible feeding means, and means for actuating and controlling rotation of each of said members including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed, said last mentioned means comprising means for rotating one of said other coaxial members separately or both simultaneously in the same direction. 10
16. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously in opposite directions. 20
17. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal axes, two of which support coaxial gear members and another of which supports planet means meshing with said gear members, means for operatively connecting one of said coaxial members to said feed operating member, and means cooperating with said other coaxial members to cause said member to rotate the latter at a predetermined cutting, a predetermined higher sumping, and a predetermined still higher machine moving speed. 30
18. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal axes, two of which support coaxial gear members and another of which supports planet means meshing with said gear members, means for operatively connecting one of said coaxial members to said feed operating member, and means cooperating with said other coaxial members to cause said member to rotate the latter at a cutting, a higher sumping, and a still higher machine moving speed, said last mentioned means comprising means for rotating one of said other coaxial members separately or both simultaneously in the same direction. 40
19. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed, said last mentioned means comprising means for rotating one of said other coaxial members separately or both simultaneously in the same direction. 50
20. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously in the same direction. 60

bers separately or both simultaneously in opposite directions.

21. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed.

22. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cutting, a predetermined higher sumping, and a predetermined still higher machine moving speed, said last mentioned means comprising means for rotating one of said other coaxial members separately or both simultaneously.

23. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a predetermined cut-

ting, a predetermined higher sumping, and a predetermined still higher machine moving speed, said last mentioned means comprising means for rotating one of said other coaxial members separately or both simultaneously in the same direction.

24. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously in opposite directions.

25. In a mining machine, a motor, cutting mechanism driven thereby, and feeding means driven by said motor including coaxial elements rotating on horizontal axes, planet means cooperating directly therewith, means for rotating each of said coaxial elements to effect operation of said planet means, and a feed operating member adapted to cooperate with flexible feeding means and rotatable on orbital movement of said planet means.

26. In a mining machine, a motor, cutting mechanism driven thereby, and feeding means driven by said motor including coaxial elements rotating on horizontal axes, planet means cooperating directly therewith, means for rotating one of them in opposite directions at different speeds to control operation of said planet means, and a feed operating member adapted to cooperate with flexible feeding means and rotatable on orbital movement of said planet means.

27. In a mining machine, a motor, cutting mechanism driven thereby, and feeding means driven by said motor including coaxial elements, planet means cooperating directly therewith, means for rotating said coaxial elements to effect operation of said planet means including means for rotating one of them continuously during feeding and the other at will, and a feed operating member adapted to cooperate with flexible feeding means and rotatable on orbital movement of said planet means, said coaxial elements having horizontal axes.

28. In a mining machine, a motor, cut-

meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously but at different angular rates.

36. In a mining machine, a motor, cutting mechanism driven thereby, and feeding means including a feed operating member adapted to cooperate directly with flexible feeding means, and means for actuating and controlling rotation of said member including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously in the same direction but at different angular rates.

37. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously but at different angular rates.

38. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members, two of which support coaxial

gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously in the same direction but at different angular rates.

39. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously but at different angular rates.

40. In a mining machine, a motor, cutting mechanism driven thereby, and feeding means including a plurality of feed operating members each adapted to cooperate directly with flexible feeding means, and means for actuating and controlling rotation of each of said members including a plurality of coaxial members rotating on horizontal axes, two of which support coaxial gear members and another of which supports planet means meshing with said gear members, means for operatively connecting one of said coaxial members to said feed operating member, and means cooperating with said other coaxial members to cause said member operatively connected with said feed operating member to rotate the latter at a cutting, a higher sumping, and a still higher machine moving speed, said last mentioned means comprising means for rotating one of said other coaxial members separately or both simultaneously in the same direction but at different angular rates.

41. In a mining machine, a motor, cutting mechanism driven thereby, and feeding means including a plurality of feed operating members each adapted to cooperate directly with flexible feeding means, and

means for actuating and controlling rotation of each of said members including a plurality of coaxial members rotating on horizontal longitudinally extending axes, two of which support coaxial gear members and another of which supports planet means meshing with said gear members, means for operatively connecting one of said coaxial members to said feed operating member, and 5 means cooperating with said other coaxial members to cause said member operatively connected with said feed operating member to rotate the latter at a cutting, a higher sumping, and a still higher machine moving 10 speed, said last mentioned means comprising means for rotating one of said other coaxial members separately or both simultaneously but at different angular rates.

42. In a mining machine, a motor, cutting mechanism driven thereby, and feeding means including a plurality of feed operating members each adapted to cooperate directly with flexible feeding means, and means for actuating and controlling rotation 25 of each of said members including a plurality of coaxial members rotating on horizontal longitudinally extending axes, two of which support coaxial gear members and another of which supports planet means meshing with said gear members, means for operatively connecting one of said coaxial members to said feed operating member, and means cooperating with said other coaxial members to cause said member operatively 30 connected with said feed operating member to rotate the latter at a cutting, a higher sumping, and a still higher machine moving speed, said last mentioned means comprising means for rotating one of said other coaxial 35 members separately or both simultaneously in the same direction but at different angular rates.

43. In a mining machine, a motor, cutting mechanism driven thereby, and feeding means driven by said motor including coaxial elements rotating on horizontal axes, planet means cooperating directly therewith, separate means for rotating each of said coaxial elements, and a feed operating member adapted to cooperate with flexible feeding means and rotatable on orbital movement of said planet means.

44. In a mining machine, a motor, cutting mechanism driven thereby, and feeding means driven by said motor including coaxial elements, planet means cooperating directly therewith, separate means for rotating said coaxial elements including means for rotating one of them continuously during feeding and the other at will, and a feed operating member adapted to cooperate with flexible feeding means and rotatable on orbital movement of said planet means, said coaxial elements having horizontal axes.

45. In a mining machine, a motor, cutting

mechanism driven thereby, and feeding means driven by said motor including a plurality of feed operating members adapted to cooperate with flexible feeding means, and means for independently driving said members selectively at a predetermined slow cutting speed, a relatively high predetermined positioning speed, and an intermediate predetermined sumping speed. 70

46. In a mining machine, a motor, cutting mechanism driven thereby, and feeding means driven by said motor including a plurality of feed operating members rotatable in opposite directions and adapted to cooperate with flexible feeding means, and means for independently driving said members selectively at a predetermined slow cutting speed, a relatively high predetermined positioning speed, and an intermediate predetermined sumping speed. 75

47. In a mining machine, a motor, cutting mechanism driven thereby, and feeding means driven by said motor including a plurality of feed operating members rotatable on parallel axes and adapted to cooperate with flexible feeding means, and means for independently driving said members at a predetermined slow cutting speed, a relatively high predetermined positioning speed, and an intermediate predetermined sumping speed. 80

48. In a mining machine, a motor, cutting mechanism driven thereby, and feeding means driven by said motor including a plurality of feed operating members rotatable on parallel horizontally disposed axes and adapted to cooperate with flexible feeding means, and means for independently driving said members at a predetermined slow cutting speed, a relatively high predetermined positioning speed, and an intermediate predetermined sumping speed. 100

49. In a mining machine, a motor, cutting mechanism driven thereby, and feeding means driven by said motor including a plurality of feed operating members rotatable on parallel horizontally disposed axes extending longitudinally of the machine and adapted to cooperate with flexible feeding means, and means for independently driving said members at a predetermined slow cutting speed, a relatively high predetermined positioning speed, and an intermediate predetermined sumping speed. 110

50. In a mining machine, a motor, cutting mechanism driven thereby, and feeding means driven by said motor including a plurality of feed operating members adapted to cooperate with flexible feeding means, and means for either independently or simultaneously driving said members at a predetermined slow cutting speed, a relatively high predetermined positioning speed, and an intermediate predetermined sumping speed. 120

125

130

51. In a mining machine, a motor, cutting mechanism driven thereby, and feeding means driven by said motor including a plurality of feed operating members adapted to cooperate with flexible feeding means, and means for driving said members at a predetermined slow cutting speed, a predetermined relatively high positioning speed and an intermediate predetermined sumping speed including a clutch and brake controlling each feed operating member.

52. In a mining machine, a motor, cutting mechanism driven thereby, and feeding means driven by said motor including a plurality of feed operating members adapted to cooperate with flexible feeding means, and means for driving said members at a predetermined slow cutting speed, a predetermined relatively high positioning speed and an intermediate predetermined sumping speed including a clutch and brake controlling each feed operating member and disposed coaxially therewith.

53. In a mining machine, a motor, cutting mechanism driven thereby, and feeding means driven by said motor including a plurality of feed operating members adapted to cooperate with flexible feeding means, and means for independently driving said mem-

bers selectively at a slow cutting speed, a relatively high positioning speed and an intermediate sumping speed including a planetary plural predetermined speed change speed mechanism individual to each feed operating member.

54. In a mining machine, a motor, cutting mechanism driven thereby, and feeding means driven by said motor including a plurality of feed operating members adapted to cooperate with flexible feeding means, and means for driving said members at three predetermined speeds including a planetary change speed mechanism individual to each feed operating member.

55. In a mining machine, a motor, cutting mechanism driven thereby, and feeding means driven by said motor including a plurality of feed operating members adapted to cooperate with flexible feeding means, and means for driving said members at a plurality of predetermined speeds including a planetary change speed mechanism individual to each feed operating member, each of said change speed mechanisms including a reaction member adapted to be held stationary to effect one driving speed.

In testimony whereof I affix my signature.

LOUIS A. MAXSON.

CERTIFICATE OF CORRECTION.

Patent No. 1,662,795.

Granted March 13, 1928, to

LOUIS A. MAXSON.

It is hereby certified that error appears in the printed specification of the above numbered patent requiring correction as follows: Page 2, line 1, for the word "work" read "worm" and line 10, for the word "an" read "one"; and that the said Letters Patent should be read with these corrections therein that the same may conform to the record of the case in the Patent Office.

Signed and sealed this 10th day of April, A. D. 1928.

(Seal)

M. J. Moore,
Acting Commissioner of Patents.
